Extraction valve 100 includes main body section 10, first inflow port portion 11a, second inflow port portion 12a, extraction section 12, first flow path 11b, second flow path 12b, first valve body 13 and second valve body 14, push-in bar 15, and cock 18 connected to an end of push-in bar 15 and used to rotate push-in bar 15. One or both of first valve body 13 and second valve body 14 are moved back and forth on the basis of the rotation of push-in bar 15, and first flow path 11b is opened and closed by the back-and-forth movement of first valve body 13 and second flow path 12b is opened and closed by the back-and-forth movement of second valve body 14.

1
EXTRACTION VALVE

TECHNICAL FIELD

The present invention relates to an extraction valve, and more specifically to an extraction valve into which a first beverage and a second beverage are respectively allowed to independently flow and which enables the first beverage, the second beverage, or the first beverage and the second beverage to be selectively extracted from one extraction section.

BACKGROUND ART

In a restaurant or the like, an extraction valve for extracting from a beverage stored in large amounts an appropriate amount of the beverage has been used.

In the extraction valve, not only allowing one type of beverage to flow thereto and extracting the beverage in a timely manner but also respectively allowing an undiluted solution and a diluted solution such as water or a foamed solution to independently flow thereto and extracting them in a timely manner, for example, has been performed.

Known as an example of the extraction valve is a beverage extraction valve including a valve main body, a dilution water flow path connected to the valve main body and supplying dilution water to the valve main body, a beverage undiluted solution flow path connected to the valve main body and supplying a beverage undiluted solution to the valve main body, a dilution water supply valve provided in the dilution water flow path, a beverage undiluted solution supply valve provided in the beverage undiluted solution flow path, and an operation lever provided in an upper part of the valve main body, and being openable and closable by moving the operation lever in a slide hole and selectively pressing either one or both of the dilution water supply valve and the beverage undiluted solution supply valve in a predetermined pressing direction depending on its position (see, e.g., Patent Literature 1).

In the above-described beverage extraction valve, the operation lever is provided in the slide hole in the upper part of the valve main body. Accordingly, contaminants such as dust and droplets of a beverage may enter the operation lever from the slide hole and adhere thereto. Accordingly, the contaminants may prevent the operation lever from moving and thus cause a failure of the beverage extraction valve.

On the other hand, there has been known a liquid extraction device including an extraction section having a foamed solution flow path through which a foamed solution flows and an undiluted solution flow path through which an undiluted solution flows formed therein and an extraction nozzle section having a foamed solution extraction port portion communicating with the foamed solution flow path and for extracting the foamed solution and an undiluted solution extraction port portion communicating with the undiluted solution flow path and for extracting the undiluted solution, and being adapted such that the foamed solution flow path and the undiluted solution flow path are respectively provided with open/close valves and the open/close valves are opened and closed in synchronization with an operation of a cock provided beside the extraction section (see, i.e., Patent Literature 2). According to the liquid extraction device, the cock is provided beside the extraction section, thereby making it possible to prevent contaminants from entering the extraction section.

CITATION LIST

Patent Literature

5 PTL 1: Japanese Patent Application Laid-Open No. 2018-20804

10 PTL 2: Japanese Patent Application Laid-Open No. 2019-209988

SUMMARY OF INVENTION

Technical Problem

In the conventional extraction valve including the beverage extraction valve described in Patent Literature 1, its internal structure varies. However, the extraction valve generally has a disadvantage of being difficult to repair and maintain because it has a large number of components and has a complicated internal structure.

15 20 The present invention has been made in view of the above-described circumstances, and is directed to providing an extraction valve capable of preventing entrance of contaminants and enabling a first beverage, a second beverage, or the first beverage and the second beverage to be selectively extracted even with a simple internal structure.

Solution to Problems

The inventors of the present invention have intensively 30 studied to solve the above-described problem and found that the above-described problem can be solved by connecting a cock for rotating a push-in bar inserted into a main body section to an exposed end of the push-in bar and moving one or both of a first valve body and a second valve body 35 contained in the main body section back and forth on the basis of the rotation of the push-in bar, thereby completing the present invention.

The present invention resides in (1) an extraction valve 40 into which a first beverage and a second beverage are respectively allowed to independently flow and which enables the first beverage, the second beverage, and the first beverage and the second beverage to be selectively extracted from one extraction section, the extraction valve including a main body section having a cylindrical trapezoidal shape, a first inflow port portion and a second inflow port portion provided in a back portion of the main body section, the extraction section provided on a side surface of the main body section, a first flow path provided in the main body section and connecting the first inflow port portion and the extraction section to each other, a second flow path provided in the main body section and connecting the second inflow port portion and the extraction section to each other, a first valve body contained in the main body section and including the first valve portion inserted into the first flow path and a 50 first support portion supporting the first valve portion, a second valve body contained in the main body section and including a second valve portion inserted into the second flow path and a second support portion supporting the second valve portion, a push-in bar which is inserted into the main body section and with which the first valve body and the second valve body are brought into contact, and a cock 55 connected to an end, which is exposed from the main body section, of the push-in bar and used to rotate the push-in bar, in which one or both of the first valve body and the second valve body are moved back and forth on the basis of the rotation of the push-in bar, and the first flow path is opened and closed by the back-and-forth movement of the first valve 60 65

body and the second flow path is opened and closed by the back-and-forth movement of the second valve body.

The present invention resides in (2) the extraction valve described in the foregoing item (1), in which the push-in bar is slideable to be located at a first position, a second position, and a third position in an axial direction of the push-in bar, only the first valve body moves back and forth when the push-in bar is rotated using the cock if the push-in bar is located at the first position, only the second valve body moves back and forth when the push-in bar is rotated using the cock if the push-in bar is located at the second position, and both the first valve body and the second valve body move back and forth when the push-in bar is rotated using the cock if the push-in bar is located at the third position.

The present invention resides in (3) the extraction valve described in the foregoing item (2), in which the push-in bar is movable between the first position and the second position, and a position on one side is the first position, a position on the other side is the second position, and a position between the first position and the second position is the third position.

The present invention resides in (4) the extraction valve described in the foregoing item (2) or (3), in which the push-in bar includes a quarter-semicylindrical portion at its center, semicylindrical portions respectively provided to be continuous to both sides of the quarter-semicylindrical portion, and cylindrical portions respectively provided to be continuous to the semicylindrical portions, an end of the first support portion on the opposite side to the first valve portion is brought into contact with the semicylindrical portion and an end of the second support portion on the opposite side to the second valve portion is brought into contact with the quarter-semicylindrical portion at the first position, an end of the first support portion on the opposite side to the first valve portion is brought into contact with the quarter-semicylindrical portion and an end of the second support portion on the opposite side to the second valve portion is brought into contact with the semicylindrical portion at the second position, and an end of the first support portion on the opposite side to the first valve portion and an end of the second support portion on the opposite side to the second valve portion are brought into contact with the semicylindrical portion at the third position.

The present invention resides in (5) the extraction valve described in any one of the foregoing items (1) to (4), in which the first support portion and the second support portion each have a stick shape, and their respective axial directions are parallel to each other.

The present invention resides in (6) the extraction valve described in any one of the foregoing items (1) to (5), in which the first valve body further includes a first head portion provided on the opposite side to the first valve portion with respect to the first support portion, the second valve body further includes a second head portion provided on the opposite side to the second valve portion with respect to the second support portion, a first spring body sandwiched between the first head portion and a first receiving stand formed in the main body section is attached to the first valve body, and a second spring body sandwiched between the second head portion and a second receiving stand formed in the main body section is attached to the second valve body.

The present invention resides in (7) the extraction valve described in any one of the foregoing items (1) to (6), in which the first valve body further includes a first head portion provided on the opposite side to the first valve portion with respect to the first support portion and a first cover portion covering the first head portion, the second

valve body further includes a second head portion provided on the opposite side to the second valve portion with respect to the second support portion and a second cover portion covering the second head portion, the first cover portion is detachably attached to the first head portion, the second cover portion is detachably attached to the second head portion, and the first cover portion and the second cover portion are brought into contact with the push-in bar.

The present invention resides in (8) the extraction valve described in any one of the foregoing items (1) to (7), in which the first beverage is an undiluted solution, and the second beverage is a foamed solution, the extraction section includes a pipe section having a cylindrical shape contained in the main body section, a flow rate adjuster arranged inside the pipe section, an acceptor attached to a lower end of the flow rate adjuster, a spacer having a cylindrical shape attached to the main body section and arranged to surround the flow rate adjuster and the acceptor, and a nozzle section having a cylindrical shape attached to the main body section and arranged outside the spacer, the first beverage flows between the spacer and the nozzle section and is extracted, and the second beverage flows between the flow rate adjuster and the pipe and is guided to the acceptor and extracted from inside the spacer.

Advantageous Effects of Invention

In the extraction valve according to the present invention, the push-in bar is rotated using the cock, whereby one or both of the first valve body and the second valve body are selectively moved back and forth. This makes it possible to selectively extract the first beverage, the second beverage, or the first beverage and the second beverage.

In the extraction valve, the cock for rotating the push-in bar inserted into the main body section is connected to the exposed end of the push-in bar, thereby preventing contaminants such as dust and droplets of a beverage from entering the main body section. As a result, a failure caused by the contaminants can be prevented from occurring.

The above-described extraction valve has a simple internal structure in which the first valve body, the second valve body, and the push-in bar are attached to the inside of the main body section provided with the two flow paths and the like. Accordingly, the extraction valve has a relatively small number of components, and is significantly easy to repair and maintain.

In the extraction valve according to the present invention, the valve body to be moved back and forth is merely made switchable depending on the position of the push-in bar (the first position, the second position, and the third position), thereby making it possible to selectively extract the first beverage, the second beverage, and the first beverage and the second beverage in a simple operation of pushing and pulling the push-in bar in its axial direction to change the position. At this time, the push-in bar is made movable between the first position and the second position, whereby a position moved to its one end, a position moved to the other end, and an intermediate position therebetween can be respectively set as the first position, the second position, and the third position. Then, the first position, the second position, and the third position can be clearly distinguished, thereby making it difficult for a malfunction to occur.

In the extraction valve according to the present invention, the push-in bar includes the quarter-semicylindrical portion, the semicylindrical portions, and the cylindrical portions, for example, thereby making it possible to selectively extract

the first beverage, the second beverage, and the first beverage and the second beverage depending on the position of the push-in bar.

That is, an end of the first support portion on the opposite side to the first valve portion is brought into contact with the semicylindrical portion and an end of the second support portion on the opposite side to the second valve portion is brought into contact with the quarter-semicylindrical portion at the first position, an end of the first support portion on the opposite side to the first valve portion is brought into contact with the quarter-semicylindrical portion and an end of the second support portion on the opposite side to the second valve portion is brought into contact with the semicylindrical portion at the second position, and an end of the first support portion on the opposite side to the first valve portion and an end of the second support portion on the opposite side to the second valve portion are brought into contact with the semicylindrical portion at the third position.

In the extraction valve according to the present invention, the first support portion and the second support portion each have a stick shape, and the respective axial directions are made parallel to each other, thereby making it possible to efficiently and smoothly perform the back-and-forth movements by the push-in bar.

In the extraction valve according to the present invention, the first spring body and the second spring body are attached. Thus, the first valve body pushed by the push-in bar is restored to its original position with a spring force of the first spring body, and the second valve body pushed by the push-in bar is restored to its original position with a spring force of the second spring body. This makes it possible for the extraction valve to have a simpler internal structure.

In the extraction valve according to the present invention, if the first valve body includes a first cover portion covering the first head portion, the second valve body includes a second cover portion that covers the second head portion, and the first cover portion and the second cover portion are brought into contact with the push-in bar, the first cover portion is rubbed with the push-in bar instead of the first head portion when the push-in bar rotates to push the first valve body and the second cover portion is rubbed with the push-in bar instead of the second head portion when the second valve body is pushed.

This makes it possible to prevent the first head portion and the second head portion from being rubbed to wear. The first cover portion is detachably attached to the first head portion, and the second cover portion is detachably attached to the second head portion. Accordingly, if the first cover portion or the second cover portion wears, only the cover portion may be replaced.

In the extraction valve according to the present invention, if the first beverage is an undiluted solution and flows between the spacer and the nozzle section and is extracted, and the second beverage is a foamed solution and flows between the flow rate adjuster and the pipe and is guided to the acceptor and extracted from inside the spacer, a high carbonate concentration of the foamed solution can be maintained, and the undiluted solution, the foamed solution, or the undiluted solution and the foamed solution can be selectively extracted.

BRIEF DESCRIPTION OF DRAWINGS

FIG. 1(a) is a side view illustrating an embodiment of an extraction valve according to the present invention.

FIG. 1(b) is a rear view of the extraction valve illustrated in FIG. 1(a).

FIG. 2 is a cross-sectional view taken along a line A-A of the extraction valve illustrated in FIG. 1(b).

5 FIG. 3 is a broken perspective view of the extraction valve according to the present embodiment.

FIG. 4 is a perspective view illustrating a push-in bar and a cock in the extraction valve according to the present embodiment.

10 FIG. 5 is an explanatory view for describing respective movements of a valve body at positions, i.e., a first position, a second position, and a third position in the extraction valve according to the present embodiment.

FIG. 6 is a cross-sectional view taken along a line B-B of the extraction valve illustrated in FIG. 1(b).

15 FIG. 7(a) is a cross-sectional view illustrating an extraction valve according to another embodiment.

FIG. 7(b) is a transmission perspective view of the extraction valve according to the other embodiment.

DESCRIPTION OF EMBODIMENTS

A preferred embodiment of the present invention will be described in detail below with reference to the drawings, as needed. In the drawings, the same elements are respectively assigned the same reference numerals, and overlapping description is omitted. Dimensional ratios in the drawings are not limited to illustrated ratios.

In the specification, the extraction section side in a length direction of a main body section is set as "front", and the inflow port portion side in the length direction of the main body section is set as "rear". That is, "front-rear direction" means the length direction (a horizontal direction in FIG. 1) of the main body section, and "back-and-forth movement" means reciprocation in the length direction of the main body section.

"Radial direction" means a direction (a vertical direction in FIG. 1) perpendicular to the length direction of the main body section.

40 FIG. 1(a) is a side view illustrating an embodiment of an extraction valve according to the present invention, and FIG. 1(b) is a rear view of the extraction valve illustrated in FIG. 1(a). In FIG. 1(b), description of a wall section W and a tube T is omitted.

45 An extraction valve 100 according to the present embodiment includes a main body section 10, an extraction section 12 provided on a side surface 10b of the main body section, a push-in bar 15 inserted into the main body section 10, and a cock 18 connected to the push-in bar 15, as illustrated in FIG. 1(a), and a first inflow port portion 11a and a second inflow port portion 12a provided in a back portion 10a of the main body section 10, as illustrated in FIG. 1(b).

The extraction valve 100 has a simple internal structure in which the push-in bar 15 and a first valve body and a second valve body, described below, are attached in the main body section 10 provided with the first inflow port portion 11a and the second inflow port portion 12a. Accordingly, the extraction valve 100 has a relatively small number of components, and is significantly easy to repair and maintain.

60 As illustrated in FIG. 1(a), in the extraction valve 100, tubes T are respectively attached to the first inflow port portion 11a and the second inflow port portion 12a, and a first beverage and a second beverage are respectively allowed to flow into the first inflow port portion 11a and the second inflow port portion 12a via the tubes T.

The first beverage and the second beverage are forcibly allowed to flow into the extraction valve 100 with prede-

terminated pressure by gas pressure, a pump, or the like. Such pressure is always maintained. Accordingly, when the valve body opens the flow path, described below, the beverage flows therethrough.

The extraction valve 100 is used with the main body section 10 attached to a wall portion W of a storage tank for containing the first beverage and the second beverage, a refrigerator for refrigerating the first beverage and the second beverage, or an inclination device for inclining a container into which the first beverage or the second beverage is injected, for example. That is, the extraction valve 100 is installed such that the beverages can respectively flow from the first inflow port portion and the second inflow port portion and a container can be arranged below the extraction section 12 because the beverages are extracted from the extraction section 12.

In the extraction valve 100, when the first beverage is allowed to flow from the first inflow port portion 11a and the second beverage is allowed to flow from the second inflow port portion 12a to incline the cock 18, only the first beverage, only the second beverage, or both the first beverage and the second beverage can be selectively extracted from the one extraction section 12 depending on a position of the cock 18. A mechanism for the extraction will be described below.

Although the first beverage and the second beverage are not particularly limited, examples of the first beverage include an undiluted solution of a general beverage. When the first beverage is an undiluted solution, examples of the second beverage include a diluted solution for the undiluted solution, such as water or a foamed solution. Among them, the undiluted solution and the foamed solution are respectively appropriately used as the first beverage and the second beverage in the extraction valve 100 according to the present embodiment, as described below.

FIG. 2 is a cross-sectional view taken along a line A-A of the extraction valve illustrated in FIG. 1(b), and FIG. 3 is a broken perspective view of the extraction valve according to the present embodiment.

As illustrated in FIGS. 2 and 3, the main body section 10 has a cylindrical trapezoidal shape, and has a first flow path 11b through which the first beverage flows and a second flow path 12b through which the second beverage flows provided therein.

In the beverage valve 100, the first flow path 11b connects the first inflow port portion 11a and an internal flow path of the extraction section 12 to each other. The first beverage that has been allowed to flow from the first inflow port portion 11a flows through the first flow path 11b and is extracted from the extraction section 12.

The second flow path 12b connects the second inflow port portion 12a and the internal flow path of the extraction section 12 to each other. The second beverage that has been allowed to flow from the second inflow port portion 12a flows through the second flow path 12b and is extracted from the extraction section 12.

At this time, in the extraction valve 100, the first flow path 11b has a structure including a first large-diameter portion 11b1 having a larger diameter than that of the first flow path 11b in its middle and extending in a front-rear direction from the first inflow port portion 11a to the first large diameter portion 11b1 and extending in an oblique direction toward the internal flow path of the extraction section 12 from the first large diameter portion 11b1.

Similarly, the second flow path 12b has a structure including a second large-diameter portion 12b1 having a larger diameter than that of the second flow path 12b in its middle

and extending in a front-rear direction from the second inflow port portion 12a to the second large diameter portion 12b1 and extending in an oblique direction toward the internal flow path of the extraction section 12 from the second large diameter portion 12b1.

In the main body section 10, a first insertion hole 20a communicating with the first large diameter portion 11b1 and a second insertion hole 20b communicating with the second large diameter portion 12b1 are respectively formed 10 separately from the first flow path 11b and the second flow path 12b.

The first flow path 20a is located on the same straight line 15 as that of the first flow path 11b from the first inflow port portion 11a to the first large diameter portion 11b1, described above, and the second flow path 20b is located on the same straight line as that of the second flow path 12b from the second inflow port portion 12a to the second large diameter portion 12b1, described above. Accordingly, 20 respective back-and-forth movements of the first valve body 13 and the second valve body 14 are significantly smoothly performed.

The main body section 10 contains the first valve body 13 and the second valve body 14 that are movable back and forth.

25 The first valve body 13 includes a first valve portion 13a, a first support portion 13b supporting the first valve portion 13a, a first head portion 13c provided at an end of the first support portion 13b on the opposite side to the first valve portion 13a, and a first cover portion 13d for covering the first head portion 13c.

30 Similarly, the second valve body 14 includes a second valve portion 14a, a second support portion 14b supporting the second valve portion 14a, a second head portion 14c provided at an end of the second support portion 14b on the opposite side to the second valve portion 14a, and a second cover portion 14d for covering the second head portion 14c.

35 The first valve body 13 is formed by integrating the first valve portion 13a, the first support portion 13b, the first head portion 13c, and the first cover portion 13d and has a stick shape extending in a front-rear direction, and the second valve body 14 is formed by integrating the second valve portion 14a, the second support portion 14b, the second head portion 14c, and the second cover portion 14d and has a stick shape extending in a front-rear direction.

40 The first valve portion 13a is inserted into the first large diameter portion 11b1 in the first flow path 11b, and the first support portion 13b is inserted into the first insertion hole 20a.

45 The first valve portion 13a moves back and forth in the first large diameter portion 11b1 on the basis of the back-and-forth movement of the first valve body 13. That is, the first flow path 11b is closed when the first valve portion 13a is brought into contact with the first large diameter portion 11b1, and is opened when the first valve portion 13a deviates from the first large diameter portion 11b1.

50 Similarly, the second valve portion 14a is inserted into the second large diameter portion 12b1 in the second flow path 12b, and the second support portion 14b is inserted into the second insertion hole 20b.

55 The second valve portion 14a moves back and forth in the second large diameter portion 12b1 on the basis of the back-and-forth movement of the second valve body 14. That is, the second flow path 12b is closed when the second valve portion 14a is brought into contact with the second large diameter portion 12b1, and is opened when the second valve portion 14a deviates from the second large diameter portion 12b1.

Both the first support portion **13b** and the second support portion **14b** each have a stick shape, and their respective axial directions are parallel to each other. That is, the first insertion hole **20a** and the second insertion hole **20b**, described above, are formed parallel to each other. This makes it possible to efficiently and smoothly perform the back-and-forth movements by the push-in bar **15**.

In the extraction valve **100**, a first spring body **22a** having a coil shape is attached to the first valve body **13**. Specifically, the first support portion **13b** is inserted into the first spring body **22a**, and the first spring body **22a** has its one end brought into contact with the first head portion **13c** having a larger diameter than that of the first support portion **13b** and its other end brought into contact with a first receiving stand **21a** formed in the first insertion hole **20a** in the main body section **10**. That is, the first spring body **22a** sandwiched between the first head portion **13c** and the first receiving stand **21a** is attached to the first valve body **13**.

Similarly, a second spring body **22b** having a coil shape is attached to the second valve body **14**. Specifically, the second support portion **14b** is inserted into the second spring body **22b**, and the second spring body **22b** has its one end brought into contact with the second head portion **14c** having a larger diameter than that of the second support portion **14b** and its other end brought into contact with a second receiving stand **21b** formed in the second insertion hole **20b** in the main body section **10**. That is, the second spring body **22b** sandwiched between the second head portion **14c** and the second receiving stand **21b** is attached to the second valve body **14**.

The first spring body **22a** does not interfere with the back-and-forth movement of the first valve body **13** except that the first head portion **13c** is urged toward the front side (i.e., toward the push-in bar **15** side).

Similarly, the second spring body **22b** does not interfere with the back-and-forth movement of the second valve body **14** except that the second head portion **14c** is urged toward the front side (i.e., toward the push-in bar **15** side).

In the extraction valve **100**, the first valve body **13** pushed by the push-in bar **15** is restored to its original position with a spring force of the first spring body **22a**, and the second valve body **14** pushed by the push-in bar **15** is restored to its original position with a spring force of the second spring body **22b**. This makes it possible to more simplify the internal structure of the extraction valve **100**.

In the extraction valve **100**, the first cover portion **13d** is located at an end of the first support portion **13b** on the opposite side to the first valve portion **13a**, and is attached to cover the first head portion **13c**.

Similarly, the second cover portion **14d** is located at an end of the second support portion **14b** on the opposite side to the second valve portion **14a**, and is attached to cover the second head portion **14c**.

The first cover portion **13d** and the second cover portion **14d** are each brought into contact with the push-in bar.

That is, in the extraction valve **100**, the first valve body **13** is brought into contact with the push-in bar **15** via the first cover portion **13d**, and the second valve body **14** is brought into contact with the push-in bar **15** via the second cover portion **14d**.

Then, in the extraction valve **100**, the first cover portion **13d** is rubbed with the push-in bar **15** instead of the first head portion **13c** when the push-in bar **15** rotates to push the first valve body **13**, and the second cover portion **14d** is rubbed with the push-in bar instead of the second head portion **14c** when the second valve body **14** is pushed.

At this time, the first cover portion **13d** is detachably attached to the first head portion **13c**, and the second cover portion **14d** is detachably attached to the second head portion **14c**. Accordingly, in the extraction valve **100**, even when the first cover portion **13d** or the second cover portion **14d** is rubbed with the push-in bar **15** to wear, only the cover portion can be easily replaced.

Referring to FIG. 1(a) and FIG. 1(b) again, the cock **18** is connected to an end of the push-in bar **15**, and the push-in bar **15** is rotated in synchronization with an operation of the cock **18**. That is, the push-in bar **15** rotates on the basis of inclination of the cock **18**. Accordingly, the cock **18** is connected to an exposed end of the push-in bar **15**, thereby preventing contaminants such as dust and droplets of a beverage from entering the main body section **10**. As a result, a failure caused by the contaminants can be prevented from occurring.

The push-in bar **15** has a stick shape extending in a radial direction of the main body section **10**, and is attached to the main body section by being loosely inserted thereinto.

The push-in bar **15**, together with the cock **18**, is slidable in an axial direction of the push-in bar **15** (in a radial direction of the main body section **10**) with respect to the main body section **10** (see FIG. 1(b)).

FIG. 4 is a perspective view illustrating a push-in bar and a cock in an extraction valve according to the present embodiment.

As illustrated in FIG. 4, the push-in bar **15** includes a quarter-semicylindrical portion **15a** having a quarter-semicylindrical shape located at its center, semicylindrical portions **15b** each having a semicylindrical shape respectively provided to be continuous to both sides of the quarter-semicylindrical portion **15a**, and cylindrical portions **15c** each having a cylindrical shape respectively provided to be continuous to the semicylindrical portions **15b**. That is, the push-in bar **15** has a structure in which a part of a so-called round bar is notched and the cylindrical portion **15c**, the semicylindrical portion **15b**, the quarter-semicylindrical portion **15a**, the semicylindrical portion **15b**, and the cylindrical portion **15c** are sequentially formed continuously.

In the push-in bar **15**, the cock **18** is attached to the cylindrical portion **15c** on one side, and a stopper **15d** having a larger diameter than that of the cylindrical portion **15c** is provided in the cylindrical portion **15c** on the other side.

In the push-in bar **15**, at least the semicylindrical portions **15b** and the quarter-semicylindrical portion **15a** are located in the main body section **10**, and the cock **18** and the stopper **15d** are exposed from the main body section **10**.

Sliding in the axial direction of the push-in bar **15** is limited when the cock **18** or the stopper **15d** is brought into contact with an outer peripheral surface of the main body section **10**.

Even if the push-in bar **15** slides, the semicylindrical portions **15b** and the quarter-semicylindrical portion **15a** are always located in the main body section **10** by such a limitation.

The push-in bar **15** is slidable to be located at a first position, a second position, and a third position in the axial direction of the push-in bar **15**. Specifically, the push-in bar **15** is movable between the first position and the second position. A position on one side is the first position, a position on the other side is the second position, and a position between the first position and the second position is the third position. This makes it possible to clearly distinguish the first position, the second position, and the third position, making it difficult for a malfunction to occur.

11

FIG. 5 is an explanatory view for describing movements of a valve body at respective positions, i.e., the first position, the second position, and the third position in the extraction valve according to the present embodiment. In FIG. 5, a state of the extraction valve at a normal time (at a non-extraction time) is "N", a state of the extraction valve at the time when only the first beverage is extracted is "A", a state of the extraction valve at the time when the first beverage and the second beverage are extracted is "B", and a state of the extraction valve at the time when only the second beverage is extracted is "C" for convenience.

As illustrated in FIG. 5, when the extraction valve is in the state N, the push-in bar 15 is located at a third position P3 at a substantial center of the main body section 10.

At this time, a part of the first cover portion 13d is brought into contact with a plane on the notched side of the semicylindrical portion 15b in the first valve body 13, and a part of the second cover portion 14d is brought into contact with the plane on the notched side of the semicylindrical portion 15b in the second valve body 14. As a result, the first valve body 13 and the second valve body 14 are located on the front side (on the push-in bar 15 side). Thus, the first flow path is closed by the first valve portion 13a, and the second flow path is closed by the second valve portion 14a.

The extraction valve enters the state B by operating the cock 18 to rotate the push-in bar 15 from the state N. In this case, the push-in bar 15 is also located at the third position P3.

In the state B of the extraction valve, the first valve body 13 and the second valve body 14 are pushed by rotating the push-in bar 15, and the first cover portion 13d in the first valve body 13 and the second cover portion 14d in the second valve body 14 are brought into contact with a peripheral surface portion of the semicylindrical portion 15b. As a result, the first valve body 13 and the second valve body 14 move backward upon being respectively pushed by the semicylindrical portions 15b. Thus, the first flow path is opened by the first valve portion 13a, and the second flow path is opened by the second valve portion 14a.

The extraction valve is located at a first position P1 when the push-in bar 15 is slid until the cock 18 is brought into contact with the outer peripheral surface of the main body section 10 in the axial direction from the state N.

The extraction valve enters the state A when the cock 18 is operated to rotate the push-in bar 15.

In the state A of the extraction valve, the first valve body 13 is pushed by rotating the push-in bar 15, and the first cover portion 13d is brought into contact with the peripheral surface portion of the semicylindrical portion 15b. On the other hand, the second valve body 14 is not pushed by rotating the push-in bar 15 because the second cover portion 14d is brought into contact with a plane on the notched side of the quarter-semicylindrical portion 15a. As a result, the first valve body 13 is pushed by the semicylindrical portions 15b to move backward. Thus, the first flow path is opened by the first valve portion 13a. On the other hand, the second valve body 14 does not move but is located on the front side. Thus, the second flow path is closed by the second valve portion 14a.

The extraction valve is located at a second position P2 when the push-in bar 15 is slid until the stopper 15d is brought into contact with the outer peripheral surface of the main body section in the axial direction from the state N.

The extraction valve enters the state C when the cock 18 is operated to rotate the push-in bar 15.

In the state C of the extraction valve, the second valve body 14 is pushed by rotating the push-in bar 15, and the

12

second cover portion 14d is brought into contact with the peripheral surface portion of the semicylindrical portion 15b. On the other hand, the first valve body 13 is not pushed by rotating the push-in bar 15 because the first cover portion 13d is brought into contact with the plane on the notched side of the quarter-semicylindrical portion 15a. As a result, the second valve body 14 is pushed by the semicylindrical portion 15b to move backward. Thus, the second flow path is opened by the second valve portion 14a. On the other hand, the first valve body 13 does not move but is located on the front side. Thus, the first flow path is closed by the first valve portion 13a.

As a result, in the extraction valve 100, if the push-in bar is located at the first position P1, only the first valve body 13 moves backward to open the first flow path when the push-in bar is rotated using the cock 18. If the push-in bar 15 is located at the second position P2, only the second valve body 14 moves backward to open the second flow path when the push-in bar 15 is rotated using the cock 18. If the push-in bar 15 is located at the third position P3, both the first valve body 13 and the second valve body 14 move backward to respectively open the first flow path and the second flow path when the push-in bar 15 is rotated using the cock 18.

Therefore, in the extraction valve 100, the valve body to be moved back and forth can be switched by a simple operation of pushing and pulling the push-in bar 15 in the axial direction to change the position (the first position P1, the second position P2, and the third position P3).

When the push-in bar 15 is rotated depending on the position of the push-in bar 15, the first beverage, the second beverage, or the first beverage and the second beverage can be selectively extracted from the one extraction section 12.

After the push-in bar 15 pushes the first valve body 13 and/or the second valve body 14, the cock 18 is returned to its original position so that the push-in bar 15 oppositely rotates, the first spring body 22a restores the first valve body 13 to the original position with its spring force, and the second spring body 22b restores the second valve body 14 to the original position with its spring force. As a result, the extraction valve 100 returns to the state N.

Accordingly, the push-in bar 15 and the first and second valve bodies 13 and 14 are in a so-called relationship between a cam and a follower.

The extraction section 12 is provided to protrude from the side surface 10b of the main body section 10.

FIG. 6 is a cross-sectional view taken along a line B-B of the extraction valve illustrated in FIG. 1(b).

As illustrated in FIG. 6, the extraction section 12 includes a pipe section 21 having a cylindrical shape contained in the main body section 10, a flow rate adjuster 22 arranged inside the pipe section 21, an acceptor 23 attached to a lower end of the flow rate adjuster 22, a spacer 24 having a cylindrical shape attached to the main body section 10 and arranged to surround the flow rate adjuster 22 and the acceptor 23, and a nozzle section 25 having a cylindrical shape attached to the main body section 10 and arranged outside the spacer 24.

In the main body section 10, the second flow path 12b communicates with the pipe section 21, and the second beverage flowing through the second flow path 12b flows into the pipe section 21.

The second beverage flows between the pipe section 21 and the flow rate adjuster 22.

The flow rate adjuster 22 has its one end screwed into the main body section 10.

The flow rate adjuster 22 has its outer peripheral surface provided with a mesh-shaped groove.

13

When the second beverage is a foamed solution, the flow velocity of the foamed solution can be adjusted by adjusting a direction, a diameter, a depth, and the like of the groove. This makes it possible to maintain the carbon dioxide gas concentration of the foamed solution and solve a pressurized state by gas pressure, a pump, or the like.

A mesh-shaped groove can also be provided on an inner peripheral surface of the pipe section 21.

Then, the second beverage drops along an outer surface of the acceptor 23 having a dome shape attached to a lower end of the flow rate adjuster 22. This results in further decrease in drop velocity (flow velocity) of the second beverage and prevents the second beverage from being scattered in four directions.

Therefore, the second beverage flows between the flow rate adjuster 22 and the pipe 21 as an internal flow path of the extraction section 12 and is guided to the acceptor 23 and extracted from inside the spacer 24.

On the other hand, in the main body section 10, the first flow path 11b communicates with a flow path between the spacer 24 and the nozzle section 25, and the first beverage flowing through the first flow path 11b flows into the flow path.

The first beverage flows between the spacer 24 and the nozzle section 25 as an internal flow path of the extraction section 12 and is extracted.

Therefore, in the extraction valve 100, the first beverage and the second beverage are respectively extracted from different internal flow paths in the extraction section 12.

If the first beverage is an undiluted solution and the second beverage is a foamed solution, a high carbonate concentration of the foamed solution can be maintained, and the undiluted solution, the foamed solution, or the undiluted solution and the foamed solution can be selectively extracted.

Although a preferred embodiment of the present invention has been described above, the present invention is not limited to the above-described embodiment.

Although in the extraction valve 100 according to the present embodiment, the first flow path 11b has a structure including a first large-diameter portion 11b1 in its middle and extending in a front-rear direction from the first inflow port portion 11a to the first large diameter portion 11b1 and extending in an oblique direction toward the internal flow path of the extraction section 12 from the first large diameter portion 11b1, for example, the presence or absence of the first large diameter portion and the direction of the flow path are not limited to these.

The same applies to the second flow path.

Although in the extraction valve 100 according to the present embodiment, the first valve body 13 includes the first valve portion 13a, the first support portion 13b, the first head portion 13c, and the first cover portion 13d, the present invention is not limited to this if the first flow path 11b is openable and closable. The first valve body 13 may not include the first cover portion 13d so that the first head portion 13c is brought into direct contact with the push-in bar 15.

The same applies to the second valve body 14.

Although in the extraction valve 100 according to the present embodiment, the first spring body 22a is attached to the first valve body 13, and the first valve body 13 is restored to the original position with the spring force of the first spring body 22a, a method for the restoration is not limited to this.

For example, there may be provided a so-called crank mechanism, for example, for connecting the first valve body

14

and the push-in bar to each other and moving the first valve body back and forth on the basis of a direction in which the push-in bar rotates.

The same applies to the second valve body 14.

Although in the extraction valve 100 according to the present embodiment, the first position, the second position, and the third position and respective movements of the valve body at the positions are described with reference to FIG. 5, the first position, the second position, and the third position are not limited to the positions illustrated in FIG. 5, but may slightly shift from one another even within ranges where their respective functions are exhibited.

Although in the extraction valve 100 according to the present embodiment, the extraction section 12 includes the pipe section 21, the flow rate adjuster 22, the acceptor 23, the spacer 24, and the nozzle section 25, the present invention is not limited to this.

In the extraction valve 100 according to the present embodiment, a rotation prevention section for limiting rotation of the push-in bar 15 may be separately provided.

FIG. 7(a) is a cross-sectional view illustrating an extraction valve according to another embodiment, and FIG. 7(b) is a transmission perspective view of the extraction valve according to the other embodiment.

FIG. 7(b) is a diagram passing through a frame body K of an extraction valve 101 illustrated in FIG. 7(a).

As illustrated in FIGS. 7(a) and 7(b), in the extraction valve 101 according to the other embodiment, a rotation prevention section 30 for limiting rotation of a push-in bar 15 is attached.

Specifically, the rotation prevention section 30 is brought into contact with a quarter-semicylindrical portion 15a in the push-in bar 15 by rotating the push-in bar 15. This makes it possible to reliably prevent the push-in bar 15 from too rotating.

INDUSTRIAL APPLICABILITY

The extraction valve according to the present invention can be used as a device into which a first beverage and a second beverage are respectively allowed to independently flow and which enables the first beverage, the second beverage, and the first beverage and the second beverage to be selectively extracted from one extraction section.

The extraction valve according to the present invention can prevent entrance of contaminants and enables a first beverage, a second beverage, or the first beverage and the second beverage to be selectively extracted even with a simple internal structure.

The invention claimed is:

1. An extraction valve into which a first beverage and a second beverage are respectively allowed to independently flow and which enables the first beverage, the second beverage, and the first beverage and the second beverage to be selectively extracted from one extraction section, the extraction valve comprising:
  - a main body section having a cylindrical trapezoidal shape;
  - a first inflow port portion and a second inflow port portion provided in a back portion of the main body section; the extraction section provided on a side surface of the main body section;
  - a first flow path provided in the main body section and connecting the first inflow port portion and the extraction section to each other;
  - a second flow path provided in the main body section and connecting the second inflow port portion and the extraction section to each other;
  - a first valve body contained in the main body section and including a first valve portion inserted into the first flow path and a first support portion supporting the first valve portion;
  - a second valve body contained in the main body section and including a second valve portion inserted into the second flow path and a second support portion supporting the second valve portion;
  - a push-in bar which is inserted into the main body section and with which the first valve body and the second valve body are brought into contact; and
  - a cock connected to an end, which is exposed from the main body section, of the push-in bar and used to rotate the push-in bar, wherein one or both of the first valve body and the second valve body are moved back and forth on the basis of the rotation of the push-in bar,

16

the first flow path is opened and closed by the back-and-forth movement of the first valve body and the second flow path is opened and closed by the back-and-forth movement of the second valve body,
 5 the push-in bar is slideable to be located at a first position, a second position, and a third position in an axial direction of the push-in bar,
 only the first valve body moves back and forth when the push-in bar is rotated using the cock if the push-in bar is located at the first position,
 only the second valve body moves back and forth when the push-in bar is rotated using the cock if the push-in bar is located at the second position, and
 10 both the first valve body and the second valve body move back and forth when the push-in bar is rotated using the cock if the push-in bar is located at the third position.
 2. The extraction valve according to claim 1, wherein the push-in bar includes a quarter-semicylindrical portion at its center, semicylindrical portions respectively provided to be continuous to both sides of the quarter-semicylindrical portion, and cylindrical portions respectively provided to be continuous to the semicylindrical portions,
 15 an end of the first support portion on the opposite side to the first valve portion is brought into contact with the semicylindrical portion and an end of the second support portion on the opposite side to the second valve portion is brought into contact with the quarter-semicylindrical portion at the first position,
 20 an end of the first support portion on the opposite side to the first valve portion is brought into contact with the quarter-semicylindrical portion and an end of the second support portion on the opposite side to the second valve portion is brought into contact with the semicylindrical portion at the second position, and
 25 an end of the first support portion on the opposite side to the first valve portion and an end of the second support portion on the opposite side to the second valve portion are brought into contact with the semicylindrical portion at the third position.
 3. The extraction valve according to claim 1, wherein the first support portion and the second support portion each have a stick shape, and their respective axial directions are parallel to each other.
 4. The extraction valve according to claim 1, wherein the first valve body further includes a first head portion provided on the opposite side to the first valve portion with respect to the first support portion,
 30 the second valve body further includes a second head portion provided on the opposite side to the second valve portion with respect to the second support portion,
 35 a first spring body sandwiched between the first head portion and a first receiving stand formed in the main body section is attached to the first valve body, and a second spring body sandwiched between the second head portion and a second receiving stand formed in the main body section is attached to the second valve body.
 40 5. The extraction valve according to claim 1, wherein the first valve body further includes a first head portion provided on the opposite side to the first valve portion with respect to the first support portion and a first cover portion covering the first head portion,
 45 the second valve body further includes a second head portion provided on the opposite side to the second valve portion with respect to the second support portion and a second cover portion covering the second head portion,
 50 a first receiving stand formed in the main body section is attached to the first valve body, and a second receiving stand formed in the main body section is attached to the second valve body.
 55

17

valve portion with respect to the second support portion and a second cover portion covering the second head portion,
 the first cover portion is detachably attached to the first head portion,
 the second cover portion is detachably attached to the second head portion, and
 the first cover portion and the second cover portion are brought into contact with the push-in bar.

6. The extraction valve according to claim 1, wherein the first beverage is an undiluted solution, and the second beverage is a foamed solution,
 the extraction section includes a pipe section having a cylindrical shape contained in the main body section, a flow rate adjuster arranged inside the pipe section, an acceptor attached to a lower end of the flow rate adjuster, a spacer having a cylindrical shape attached to the main body section and arranged to surround the flow rate adjuster and the acceptor, and a nozzle section having a cylindrical shape attached to the main body section and arranged outside the spacer,
 the first beverage flows between the spacer and the nozzle section and is extracted, and
 the second beverage flows between the flow rate adjuster and the pipe section and is guided to the acceptor and extracted from inside the spacer.

7. The extraction valve according to claim 2, wherein the first support portion and the second support portion each have a stick shape, and their respective axial directions are parallel to each other.

8. The extraction valve according to claim 2, wherein the first valve body further includes a first head portion provided on the opposite side to the first valve portion with respect to the first support portion,
 the second valve body further includes a second head portion provided on the opposite side to the second valve portion with respect to the second support portion,
 a first spring body sandwiched between the first head portion and a first receiving stand formed in the main body section is attached to the first valve body, and a second spring body sandwiched between the second head portion and a second receiving stand formed in the main body section is attached to the second valve body.

9. The extraction valve according to claim 2, wherein the first valve body further includes a first head portion provided on the opposite side to the first valve portion with respect to the first support portion and a first cover portion covering the first head portion,
 the second valve body further includes a second head portion provided on the opposite side to the second valve portion with respect to the second support portion and a second cover portion covering the second head portion,
 the first cover portion is detachably attached to the first head portion,
 the second cover portion is detachably attached to the second head portion, and
 the first cover portion and the second cover portion are brought into contact with the push-in bar.

10. The extraction valve according to claim 2, wherein the first beverage is an undiluted solution, and the second beverage is a foamed solution,
 the extraction section includes a pipe section having a cylindrical shape contained in the main body section, a flow rate adjuster arranged inside the pipe section, an acceptor attached to a lower end of the flow rate

18

adjuster, a spacer having a cylindrical shape attached to the main body section and arranged to surround the flow rate adjuster and the acceptor, and a nozzle section having a cylindrical shape attached to the main body section and arranged outside the spacer,
 the first beverage flows between the spacer and the nozzle section and is extracted, and
 the second beverage flows between the flow rate adjuster and the pipe section and is guided to the acceptor and extracted from inside the spacer.

11. An extraction valve into which a first beverage and a second beverage are respectively allowed to independently flow and which enables the first beverage, the second beverage, and the first beverage and the second beverage to be selectively extracted from one extraction section, the extraction valve comprising:
 a main body section having a cylindrical trapezoidal shape;
 a first inflow port portion and a second inflow port portion provided in a back portion of the main body section; the extraction section provided on a side surface of the main body section;
 a first flow path provided in the main body section and connecting the first inflow port portion and the extraction section to each other;
 a second flow path provided in the main body section and connecting the second inflow port portion and the extraction section to each other;
 a first valve body contained in the main body section and including a first valve portion inserted into the first flow path and a first support portion supporting the first valve portion;
 a second valve body contained in the main body section and including a second valve portion inserted into the second flow path and a second support portion supporting the second valve portion;
 a push-in bar which is inserted into the main body section and with which the first valve body and the second valve body are brought into contact; and
 a cock connected to an end, which is exposed from the main body section, of the push-in bar and used to rotate the push-in bar, wherein one or both of the first valve body and the second valve body are moved back and forth on the basis of the rotation of the push-in bar,
 the first flow path is opened and closed by the back-and-forth movement of the first valve body and the second flow path is opened and closed by the back-and-forth movement of the second valve body,
 the push-in bar is slidable to be located at a first position, a second position, and a third position in an axial direction of the push-in bar,
 only the first valve body moves back and forth when the push-in bar is rotated using the cock if the push-in bar is located at the first position,
 only the second valve body moves back and forth when the push-in bar is rotated using the cock if the push-in bar is located at the second position,
 both the first valve body and the second valve body move back and forth when the push-in bar is rotated using the cock if the push-in bar is located at the third position,
 the push-in bar is movable between the first position and the second position, and
 a position on one side is the first position, a position on the other side is the second position, and a position between the first position and the second position is the third position.

19

12. The extraction valve according to claim 11, wherein the first support portion and the second support portion each have a stick shape, and their respective axial directions are parallel to each other.

13. The extraction valve according to claim 11, wherein the first valve body further includes a first head portion provided on the opposite side to the first valve portion with respect to the first support portion,

the second valve body further includes a second head portion provided on the opposite side to the second valve portion with respect to the second support portion,

a first spring body sandwiched between the first head portion and a first receiving stand formed in the main body section is attached to the first valve body, and a second spring body sandwiched between the second head portion and a second receiving stand formed in the main body section is attached to the second valve body.

14. The extraction valve according to claim 11, wherein the first valve body further includes a first head portion provided on the opposite side to the first valve portion with respect to the first support portion and a first cover portion covering the first head portion,

the second valve body further includes a second head portion provided on the opposite side to the second

5

10

15

20

25

20

valve portion with respect to the second support portion and a second cover portion covering the second head portion,

the first cover portion is detachably attached to the first head portion,

the second cover portion is detachably attached to the second head portion, and

the first cover portion and the second cover portion are brought into contact with the push-in bar.

15. The extraction valve according to claim 11, wherein the first beverage is an undiluted solution, and the second beverage is a foamed solution,

the extraction section includes a pipe section having a cylindrical shape contained in the main body section, a flow rate adjuster arranged inside the pipe section, an acceptor attached to a lower end of the flow rate adjuster, a spacer having a cylindrical shape attached to the main body section and arranged to surround the flow rate adjuster and the acceptor, and a nozzle section having a cylindrical shape attached to the main body section and arranged outside the spacer,

the first beverage flows between the spacer and the nozzle section and is extracted, and

the second beverage flows between the flow rate adjuster and the pipe section and is guided to the acceptor and extracted from inside the spacer.
